UNITED STATES PATENT OFFICE.

HENRY TIDEMAN, OF MENOMINEE, MICHIGAN.

TELEPHONE-RINGER.

No. 901,269.

Specification of Letters Patent.

Patented Oct. 13, 1908.

Application filed July 6, 1907. Serial No. 382,429.

To all whom it may concern:

Be it known that I, HENRY TIDEMAN, a citizen of the United States of America, and a resident of Menominee, county of Menominee, and State of Michigan, have invented a new and useful Improvement in Telephone-Ringers, of which the following is a specification.

My invention pertains to improvement in the class of devices known as telephone ringers, and particularly to those forms adapted to produce audible signals in response to alternating currents.

My invention has as its object the provision of a ringer which, when once assembled in proper adjustment, will retain that adjustment permanently, and which further has such simple structure and details as to render its assembly and adjustment a comparatively easy task.

I provide a U-shaped permanent magnet with a magnetic yoke bridging the poles thereof, the operating parts being mounted upon that yoke.

In the drawings, Figure 1 shows side view of my ringer; Fig. 2 shows a top view of Fig. 1, and Fig. 3 shows a view at right angles to Fig. 1, a part of the lower portion of the ringer being broken away, with detail tails on the line A-B shown in section.

In Fig. 1, 10 is a permanent magnet of U-shape, polarized with consequent poles which are of one polarity in the middle 10' and of opposite polarity at each of the two ends 10'', 10''. Across the ends of the magnet 10 is the magnetic yoke 11; this is perforated at 11' to permit the rod of the tapper 12 to pass through, and has two ears 11'', 11'' each of which is perforated for a screw, for mounting the ringer to the interior surface of the wooden containing box, through the wall of which the tapper 12 projects. The ends of the yoke 11 are formed up into lugs at 11' which are slotted; the screw 11' passes through the slot of the lug 11' and threads into the magnet 10, clamping the yoke 11 rigidly in place upon the magnet 10, but having inherently a possible adjustment by reason of the slots through which the screw 11' passes. Upon the magnetic yoke 11 are mounted the ringer spools or coils 13 by screws passing through the yoke 11. The cores of these spools project at 13' and bear collars 14 slidably placed upon the projecting cores. The non-magnetic yoke 15 is rigidly attached to the col-

lars 14-14 by any desired means, the means shown being a drive fit of the yoke 15 upon a shoulder in each of the collars 14, the reduced portion of the collar 14 being thereafter swaged to insure permanence. A reinforcement or bushing 16 is similarly inserted into the metal part of the non-magnetic yoke 15 to provide screw threads for the screw 17. Ears 15' upon the yoke 15 carry trunnion screws 15'' and lock nuts which support pivotally the armature 18. The armature 18 is perforated centrally to provide clearance for the screw 17 and its surrounding compression spring 17'. Non-magnetic bushings 19 are placed in the end of the cores 13' to prevent the sticking of the armature.

The assembly of the device for manufacture is as follows: The coils 13 are mounted upon the magnetic yoke 11; non-magnetic yoke 15 with its integral collars 14 is placed upon the free ends of the coils; the armature is placed in the yoke 15; the permanent magnet 10 is permanently attached to the magnetic yoke 11; the spring 17' is placed within the perforation of the armature 18; the screw 17 is passed through perforation in the magnet 10, then through the interior of the spring 17', and is threaded into the bushing 16; the device is now ready for adjustment. The screw 17 tends to draw the yoke 15 away from the heads of the spools while the spring 17', being a compression spring between the yoke 15 and the magnet 10, tends to force the yoke 15 toward the heads of the spools 13 and against the restraint of the screw 17; the armature 18, carried by the yoke 15, may therefore approach or recede with reference to the core ends 13' under control of the screw 17. The screw 17 is turned until an approximate adjustment of the armature 18 to the core ends is attained. The lock screws 14' 14' then are turned firmly to lock the collars 14 14 upon the core ends 13' 13'. In locking the collars 14 14 in this position of adjustment, it is desirable to lock the armature too close to the cores rather than too far away, and a final adjustment then may be made by turning the screw 17, an adjustment within a slight range being possible by the elasticity of the yoke 15. If the range of adjustment by the sliding of the cores 14 upon the core ends 13' is not sufficiently great, as might be true through error in manufacture of parts or through the necessity of replacing the spools

13 with spools in which the longer core terminals were not provided, the initial rough adjustment may be supplemented or may be replaced entirely by the adjustment 6 made possible by the provision of slots in the lugs 11^a, the final adjustment being made by elasticity of yoke 15 as described.

Having thus described my invention, what I claim as new and desire to secure by United 10 States Letters Patent is:

In a telephone ringer, a U-shaped permanent magnet; a magnetic yoke having its ends bent at right angles and extending parallel to the ends of said U-shaped magnet 15 for attachment thereto; electromagnets mounted upon said yoke and lying within the U of said permanent magnet; a non-magnetic yoke rigidly attached at its ends

to the free ends of the cores of said electromagnets and bearing trunnions at its median 20 part; an armature carried by said trunnions; a tapper rod secured to said armature and passing through said magnetic yoke; and an adjusting screw passing through the center of said permanent magnet and adapted to 25 flex said non-magnetic yoke whereby the adjustment of said armature to the ends of said cores may be determined, substantially as described.

Signed by me at Menominee, county of 30 Menominee and State of Michigan, in the presence of two witnesses.

HENRY TIDEMAN.
